UNITED STATES PATENT OFFICE

WILLIAM O. WETMORE, OF WASHINGTON, DISTRICT OF COLUMBIA

OIL LIBERATOR

Application filed February 3, 1930. Serial No. 425,619.

The invention relates to certain improvements in oil liberating devices of the general character shown in my prior Patent No. 1,623,371, dated April 5, 1927, the primary purpose of which is to provide a device for liberating oil in relatively small quantities in bodies of water, for the purpose of producing a film of oil on the surface of the water, which will be effective in preventing the breeding of mosquitoes and the like.

The invention is illustrated in the accompanying drawing, in which:—

Fig. 1 is an elevation, broken away in part, of the device in its normal mode of application.

Fig. 2 is a fragmentary sectional elevation illustrating a form of the device which is adapted to be sold or stored with the complement of oil therein.

In the particular form of the device shown and described in my prior patent aforesaid, the particular arrangement of the inlet for the water, comprising an elbow-shaped tube connected with the container near the bottom and extending upwardly, gave rise to frequent difficulties because of the obstruction of the inlet, especially when the apparatus was submerged in ponds or waterways having soft mud bottoms. A further difficulty with the former type of the device was due to the tendency of the latter to fail to deliver or discharge oil when submerged, which failure was apparently occasioned by the surface tension of the oil in contact with the interior of the container adjacent the discharge opening. Both of these difficulties have been overcome in the present invention by the location of the water inlet opening near the top of the container, which thereby eliminates the tendency of the inlet to be choked or obstructed by foreign material from the outside, admits the water to displace the oil at a point where the water will be forced to follow the wall of the container or sink through the body of the oil, so that the oil is displaced very slowly or gradually. Furthermore, the location of the water inlet near the top of the container insures the formation of an air pocket or space in the top of the container, the air therein being first forced out of the

discharge opening, when the device has been submerged, and said air apparently carrying with it sufficient oil to initiate the discharge of the main body of oil, which discharge is continuous until all of the oil in the receptacle has been displaced by the entering water.

Referring to the drawing, 1 indicates the body of the container, which is preferably frusto-conical in shape, as this particular shape is best adapted to serve conditions of economy of manufacture and efficiency of operation. The lower part of the body portion is closed by a substantially flat bottom 2, which may be seamed, soldered or otherwise connected to the body portion 1. In the form of the device shown, the receptacle is constructed of sheet metal, which may be tinned or galvanized, or otherwise treated, when the receptacle is to be used repeatedly. The upper portion of the body 1 terminates in a hollow threaded neck 4, which receives an interiorly threaded cap 5, which is also made of sheet metal and is preferably provided with a bail 6 by means of which the receptacle may be lifted and transported and which serves as means of attaching a float line, when the receptacle is to be recovered after the oil has been exhausted therefrom.

The center of the cap 5 is provided with an opening 7 through which the oil is discharged and it has been found necessary to form the discharge opening 7 with jagged or roughened edges to insure the discharge of the oil, as a relatively small smooth edged orifice will not properly discharge the oil, especially if the latter is of the heavier varieties. However, it has been found that the jagged edged discharge opening is entirely effective and once the discharge of the oil from the receptacle has been initiated, it is uniform and continuous until the supply of oil has been exhausted.

Formed in the side of the receptacle a short distance below the top thereof is an opening 8, which, when the vessel is submerged, admits water thereto to displace the oil. As hereinbefore stated, the placing of the water inlet opening just below the top of the receptacle not only insures the unobstructed entrance of the water to the receptacle without

any tendency of the opening to clog, but insures the establishment of an air space or pocket in the upper part of the receptacle, so that the air confined therein serves, in effect, as a priming medium to start the operation, when the device is submerged.

In order to insure the receptacle landing on its bottom, so that it will be in upright position, either when lowered or cast into the water, the bottom is provided with a weight 3, which, in the form shown, consists of a bar of iron or the like, which is welded or otherwise secured to the bottom.

In applying the device to its intended use, the oil is supplied to the receptacle through the opening at the top, after the screw cap has been removed. The amount of oil supplied will depend upon the surface area of the body of water to be treated. Under usual conditions, however, the oil content will be supplied until it reaches the level of the water inlet opening 8, which will be evidenced by sight or by the oil running out of said opening. The screw cap is then replaced and the device is ready for use and is either lowered by a float line or cast into the body of water to be treated with the oil film, when said device immediately begins to function; that is to say, the heavier water will begin to pass into the receptacle through the inlet opening 8 near the top and, moving down the side of the receptacle or through the body of the lighter oil, will displace the latter. As the whole body of oil is gradually moved upward, the first effect will be to displace the air in the air pocket or space above the water inlet 8 and the forcing of the air out of the discharge opening 7 apparently has a priming effect to insure the proper discharge of the oil, after the last of the air has been forced out.

When the receptacles are sold in unfilled condition, they are preferably provided with the discharge opening 7 and the water inlet opening 8 already formed therein. It may be found advantageous, however, under certain circumstances, to sell the receptacles with a full complement of oil in each, under which circumstances it would be necessary to either close the openings 7 and 8 by means of a plug or by a seal, or equivalent closing means, or, in the alternative, to indicate on the cap 5 and the body 1, by suitable markings or indentations, where the holes 7 and 8 are to be punched or formed. In any of these cases, it will be necessary for the user to uncover the openings which have been sealed, or to form the openings, which have been indicated by the markings, before the apparatus is applied to its intended use. It will be understood that the receptacle may be of any appropriate form that will insure the gradual discharge of the oil from the top, as the water enters the lateral inlet near the top, but, as stated, as a matter of economy of manufac-

ture and facility and efficiency in operation, the frusto-conical form, including the weighted flat bottom, is preferred.

What I claim is:

1. A device for liberating oil in bodies of water, comprising a frusto-conical container, a screw cap on the upper end having a small opening therein, and a water inlet opening in the side of the container a short distance below the top. 75

2. A device for liberating oil in bodies of water, comprising a frusto-conical container having a weighted bottom, a screw cap on the upper end having a small opening therein, and a water inlet opening in the side of the container a short distance below the top. 80

3. A device for liberating oil in bodies of water, comprising a container having a weighted bottom, a relatively small jagged edged opening in the top and a water inlet opening in the side a short distance below the top. 85

4. A device for liberating oil in bodies of water, comprising a container with a removable top closure and having a relatively small outlet opening in the top and a water inlet opening a relatively short distance below the outlet to provide an air pocket between the surface of the contained liquid and the outlet opening. 90

5. A device for liberating oil in bodies of water, comprising a container including a substantially conical vessel with a closed bottom and a removable top closure and having a relatively small outlet opening in the top and a water inlet opening a relatively short distance below the outlet to provide an air pocket between the surface of the contained liquid and the outlet opening. 100

In testimony whereof I affix my signature. 105
